[57] CLAIM

The ornamental design for an electric coffee-machine,
substantially as shown and described.

DESCRIPTION

FIG. 1 is a top, front and left side perspective view of an
electric coffee-machine showing my new design;
FIG. 2 is a right side perspective view thereof;
FIG. 3 is a left side perspective view thereof;
FIG. 4 is a front perspective view thereof;
FIG. 5 is a rear perspective view thereof;
FIG. 6 is a top plan view thereof;
FIG. 7 is a bottom plan view thereof;
FIG. 8 is a left side elevational view; and
FIG. 9 is an enlarged fragmentary sectional view taken
on line 9—9 of FIG. 3.
